FRAMING RULE

Pasquale Marino, Arlington, N. J.

Application July 12, 1946, Serial No. 683,122

7 Claims. (Cl. 33—98)

1

This invention relates to rules especially adapted for use in the building construction line, and has for one of its objects the provision of such a rule which may be quickly and easily used in a variety of different operations, as for instance the gaging of angle or slant of roofs, the actual measurement of any angularity and in the figuring of distances between certain points whose angular deviations are known.

Another object of the invention is the provision of such a rule or scale comprising a plurality of pivotally joined sections so arranged as to permit the pivotal movement of some of said sections relative to other sections so as to bear different angular relations to said sections, the stationary sections having angle denoting positions and the movable section having means for alining same with said angle denoting position.

A further object of the invention is the provision of preferably a six foot rule which may be formed into a tri-square of three equal sides and having two sections movable relative to the sides of the tri-square for assuming different angular positions relative to the said sides.

Still another object is to provide said rule with a movable central section which may be locked in predetermined position and provided with certain data which when multiplied by half the building width will give respectively the length of rafter or hypotenuse of the triangle formed thereby, the hip or valley length and roof rise.

A still further object of the invention is the provision of such a rule which may be used for laying out the vertical and horizontal cuts on the common rafter as well as the side cut between the jack and hip rafters.

Another object of the invention is to produce a device of the character described in which the maximum simplicity of construction and operation is secured.

Other objects and advantages will appear as the nature of the improvements is better understood, the invention consisting of the novel arrangement and co-relation of parts herein fully described, and illustrated in the accompanying drawings, wherein similar reference characters are used to denote similar parts throughout the several views, and finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be

understood from an illustrative rather than a restrictive standpoint.

In carrying out one form of the invention it was found advantageous to provide a six foot foldable rule and fold a portion thereof into an equilateral triangle having an angle gaging arm extending from the base to which it is pivotally secured, and releasably securing a second arm at the apex of the triangle pivotally mounted at the center of the base of the triangle and extending beyond the apex, the two other legs of the triangle forming a protractor with which both pivoted arms are adapted to cooperate for gaging an angle, the central arm also having trigonometric or other standard data to aid in the computation of the length of the unknown sides of a triangle formed by the angle gaging arm with one side of the main equilateral triangle.

In the accompanying drawings:

20 Figure 1 is a side view in elevation of the folded rule showing the central arm in an angle gaging position;

Figure 2 is a view looking from the bottom of Figure 1;

25 Figure 3 is a similar view to Figure 1, but showing the central arm in fixed position and the base arm moved into angle measuring or gaging position;

Figure 4 is a similar view to Figure 3, but showing 30 a different method of calibration of the base and arms;

Figure 5 is a fragmental side elevation of one 35 side of the triangle formed by the rule showing same as provided with pitch calibrations; and

Figure 6 is a perspective view of the rule in 40 partly folded position.

Referring now to the drawings in detail, the 45 numeral 10 indicates a preferably six foot long foldable rule composed of twelve six inch sections 11 joined together in the usual manner.

To adapt the rule for use in carrying out the objects of the present invention, it may be folded to form an equilateral triangle 12 having sides 13 and 14 each comprising two rule sections 11. The sides 13 and 14 may be provided with a plurality of openings or eyelets 15 located on lines drawn through the center of the said sides. The sides 13 and 14 are joined together by the base 16 of the triangle 12. The said base has two parallel sections 17 at the left of the center 18 and a single section 19 at the right of said center, a two section extension or arm 20 extends to the left of the base of the triangle and a three section arm 21 is pivotally secured to the base 16 at its center

(8. The arm 21 may be held perpendicular to the base 16 by means of a bolt and nut arrangement 22 at the apex of the triangle, as for example, by inserting bolt 22 through hole 22a of arm 21 so that said bolt holds together said arm 21 and sides 13 and 14 of the triangle. There are four such bolt and nut arrangements, one at the center of the base and one at each apex or intersection of the triangle, the bolt portion of the combination passes through the usual tubular joint member 27 between the rule sections.

In Figure 1, the arm 21 is shown as disconnected from the bolt and nut arrangement 22 at the apex of the triangle and is free to be swung about its pivot at 18 in order to measure or gage an angle which the center line of said arm makes with any of the bushings or openings 15 in the sides 13 and 14 of the triangle. The said openings 15 form protractor graduations which may be spaced at intervals of five degrees, the graduations on the right side running from zero to ninety while those on the left run from ninety to one hundred and eighty. A pin not shown may be passed through two aligned bushings or openings 15 to maintain the arm 20 in any desired position.

In Figure 3, the rule is shown with the arm 21 held at a right angle to the base 16 and provided with numbers N, these numbers being preferably constants used in the building construction line such as, for instance, the top line is a constant which when multiplied by half the length of the building gives the length of the common rafter or hypotenuse, the second line number when so multiplied gives the length of the hip or valley rafter and the last line the rise of the roof. When using the arm 20 it may be provided with openings or bushings 15a for cooperation with the openings or bushings 15. The protractor reading for any specific angle measured by the arm 20 is one-half of the angle at the same point on the arm 14 measured by the arm 21, and is read by the inner numbers N' on the side or leg 14 of the triangle.

The constants N are given for each unit of rise on the vertical arm 21 and when the center line of same is crossed by the center line of the arm 20 at any given unit, the proper set of figures is obtained for computing the rafter lengths, etc.

In the form of the invention shown in Figures 1 to 3 the rule is divided into inches and fractions of inches, however, in the form shown in Figure 4 each six inch length, especially those comprising the base, and arms 21 and 20 are divided into ten parts. In this manner a direct reading in inches, centimeters, feet, etc. can be obtained depending upon which of the systems are being used.

There is also shown in Figure 4 that the leg or side 13 of the triangle is provided with two sets of markings 23 and 24, respectively, the former being the degrees and the latter the number of sides, thus by alining the arm 21 with any of the bushings on the leg or side 13 the number of sides of a polygon and the degrees between the sides are readily determined. Only a few of such markings are shown on the leg 13 due to the lack of space caused by the scale to which the drawing is made. The upper end of the arm 21 is shown in Figure 4 as having a second set of calibrations 25. These calibrations are used in laying out the line for the side cut along the jacks for any desired pitch.

In Figure 5, the fragment of the side 14 is there

shown as being provided with fractional indicia 26. This indicia denotes the pitch of the roof. Pitches vary from what may be termed a full pitch to a small fractional pitch. The pitch is said to be a full pitch when the rise of the roof is equal to the full width of the building and half-pitch when equal to half the width of the building. Thus, on the scale of the present invention, if the center line of the arm 20 subtends a distance equal to one-half the base of the right angle triangle, then the pitch denoted will be one-quarter pitch, if a full scale section or base length then it will denote one-half pitch, etc.

It is apparent that with the rule of the present invention, reasonably accurate estimates as to the amount of lumber necessary may be made without any special computation, and that the angular slope or length of rafters may be accurately and readily obtained, either by a direct reading or by computation made possible by the constants.

It will readily be seen that the rule may be used for accurately locating lines for both the horizontal and vertical cuts of rafters for any pitch roofs. If, for instance, the slope of the roof is represented by the arm 20 in Figure 3, then by placing the edge of the base 16 parallel to the side edge of a rafter and by marking a line at the bottom end of said rafter along the edge of the arm 20 the horizontal cut on the rafter is determined. Likewise by using the vertical arm against the rafter and marking a line at the opposite end of the rafters along an edge of the arm 20 the vertical cut is determined.

What is claimed is:

1. A foldable rule comprising a number of consecutive pivotally connected flat sections, some of the said sections being folded to form an equilateral triangle, an arm pivotally mounted intermediate the ends of one side of the triangle forming the base thereof, means at the apex of the triangle for releasably securing the said arm perpendicular to the said base, and an angle gaging arm pivotally mounted at the intersection of the said base and one of the other sides of the triangle and swingable towards the third side of the triangle for the purpose specified.

2. A device according to claim 1, wherein the angle gaging arm and the third side of the triangle have co-operating angle indicating means at various positions.

3. A device according to claim 1, wherein the angle gaging arm and the third side of the triangle have co-operating angle indicating means at various positions, and the perpendicular arm, base, and angle gaging arm are identically calibrated for the purpose specified.

4. A device according to claim 1, wherein the base and arm pivoted intermediate the ends of said base are calibrated at like predetermined points, the arm being provided with sets of numerical constants at each calibration each constant of which when multiplied by the distance between the pivot point and one end of the base will be equal to an unknown factor sought.

5. A device according to claim 1, wherein the base and arm pivoted intermediate the ends of said base are calibrated at like predetermined points, the arm being provided with sets of numerical constants at each calibration each constant of which when multiplied by the distance between the pivot point and one end of the base will be equal to an unknown factor sought, said factors being respectively the hypotenuse of

a triangle or its equivalent the length of common rafter, the hip rafter length, and roof rise.

6. A device according to claim 1 in which the angle gaging arm is composed of two pivotally connected sections.

7. A device according to claim 6 in which the angle gaging arm, the base of the triangle and the arm pivoted at the midpoint of the base are each subdivided into ten equal parts.
